UNITED STATES PATENT OFFICE.

JACOB FOOSE, OF LANCASTER, PENNSYLVANIA.

STEAMER.

SPECIFICATION forming part of Letters Patent No. 255,157, dated March 21, 1882.

Application filed December 29, 1881. (No model.)

To all whom it may concern:

Be it known that I, JACOB FOOSE, a citizen of the United States, residing at Lancaster, in the county of Lancaster and State of Pennsylvania, have invented certain Improvements 5 in Steamers, of which the following is a specification.

My invention relates to portable devices for steaming tobacco and feed, heating rooms, 10 boiling water, and for use for producing steam for any culinary or household purpose; and the objects of my improvements are, first, to prevent the passage of the water from the boiler into the feed-pipes, and, second, to firmly 15 support the boiler and heater. I attain these objects by the mechanism illustrated in the accompanying drawings, in which—

Figure 1 is a side view of my steamer, with portions of the boiler and heater cut away in 20 order to show the internal arrangement of the same; Fig. 2, a top view of the water-check, and Fig. 3 a top view, through the section *x y*, of the heater showing the heating-chamber and grate.

25 Similar letters refer to similar parts throughout the several views.

My device consists of a boiler, B, and heating apparatus A. The top of the boiler is slightly concave, and has a discharge cone or 30 dome, C, (from which the feed-pipe is supplied,) in its center. Beneath the dome C, and closing the opening of the same into the boiler B, is a circular concave water-check, D. The bottom of this check D is steam-tight, but the 35 perimeter has two valves, *v*, opposite each other, which work inwardly, each having a spring, *s*, to keep it closed unless acted upon by the escaping steam. The top *p* of the check is perforated with openings to allow the passage 40 of steam into and through the dome C, from which it passes into the feed-pipe P, supplied with a stop-cock, S. In this arrangement water is prevented from escaping from the boiler into the pipes by the water-check, 45 the perforated top of the check and the cone shape of the dome C freeing the steam from any water which may have accompanied its passage through the valves.

The boiler is supported by the annular base 50 E, of the diameter of and secured to the boiler

at its lower end. An expansion-foot, F, secured to the center of the under side of the bottom of the boiler, extends to within a short distance of the floor, and prevents too great depression of the boiler-bottom by the generation of steam. The annular base affords a firm support for the boiler, preventing the jar incidental to the passage of water between the boiler and heating-chamber yet to be mentioned, and at the same time protects the heated 55 bottom of the boiler from the passage of cold air under the same, while the expansion-foot, being shorter than the base E, supports the center of the boiler, when depressed by the pressure of the steam, without becoming a pivot 60 about which the steamer might rock, the difference in length between the foot and base being such as to compensate for the depression of the bottom caused by a working head 65 of steam.

The fire-box G of the stove A is surrounded by a water-heating chamber, I, connected with the boiler by two pipes, O and O'. The first pipe, O, connects the bottom of the boiler with the lower part of the heating-chamber, and the 70 second, O', the top of said heating-chamber with the upper part of the boiler. The use of these two pipes permits the passage of water of different temperatures between the boiler and chamber by means of different pipes, facilitating the heating of the water, and consequently the making of steam. The heating-chamber has a spigot, b, attached to it.

The side of the stove toward the boiler is upheld by the pipes O and O', and on the other 75 by one leg, g. The leg g rests in the ash-pan, and serves as a pivot about which the ash-pan is revolved in turning it from under the stove to free it from ashes. The shifting and drawing grate h is held in place by lugs l.

The boiler is supplied with water through the feeder H, which extends from the top thereof down to the bottom, the lower end curving so as to throw the water into the boiler laterally. It also has attached an escape-pipe, f, connected with the safety-valve 95 *v'*, and a whistle, w, which may be detached, if necessary, to make any other connection in its place, or form a simple blow-off and a water-gage, N.

The stove is a self-feeder, having a reservoir, *r*, for fuel. The boiler and base are built of heavy galvanized tank-iron, and the connecting-pipes and chamber *I* of heavy copper covered with galvanized iron.

The dome *C* may be shaped differently from that described, as I do not limit myself to that precise form.

What I claim as my invention, and desire to secure by Letters Patent, is—

1. The water-check *D*, having a perforated

top and valves *v*, in combination with a boiler, *B*, and dome *C*, substantially as and for the purpose specified.

2. In a steamer, the combination of the boiler *B*, annular base *E*, and the expansion-foot *F*, as and for the purpose set forth.

JACOB FOOSE.
